UNITED STATES PATENT OFFICE.

EUGÈNE MUNSCH, OF NEWARK, NEW JERSEY.

INTERNAL-COMBUSTION ENGINE.

No. 923,562.

Specification of Letters Patent.

Patented June 1, 1909.

Application filed June 25, 1908. Serial No. 440,261.

To all whom it may concern:

Be it known that I, EUGÈNE MUNSCH, a citizen of the United States, residing at Newark, in the county of Essex and State of New Jersey, have invented certain new and useful Improvements in Internal-Combustion Engines; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to internal-combustion engines or explosive gas-engines; and, the invention has reference, more particularly, to a novel construction of engine of the general character herein-after more fully set forth, the engine comprising in its construction a suitable framework formed with oppositely located cylinders into each of which the explosive gas or mixture is alternately taken in by suction, or otherwise, and each cylinder being provided with a reciprocatory piston, said pistons being connected by a connecting piston-rod, upon each free end-portion of which a piston-head is attached, and the movement of each piston being such that during its forward stroke it will take into the respective cylinder a fresh supply of the explosive mixture or gas upon one side of the piston, and will compress for explosion the previously taken in supply of explosive mixture or gas upon the other side of the piston; and, upon the return-stroke, the piston forcing the said fresh and unexploded supply of the explosive mixture or gas upon the other side of the piston, ready for compression and explosion when the piston again makes its forward stroke and simultaneously takes in another fresh supply of the explosive mixture or gas.

The invention has for its principal object to provide an internal combustion engine in which two explosions of gas take place during each complete revolution of the main shaft of the engine, and to provide an engine in which the various parts are arranged and constructed in such a manner, so as to insure efficiency and economy, and furthermore to provide a simple construction and arrangement of the various parts, so as to minimize the liability of the jam-

ming of or of injury to the parts, and especially to the valves.

A further object of this invention is to provide a novel construction of internal combustion or explosive gas-engine, the oppositely placed cylinders and pistons of which are arranged in such a manner, so that the engine can still be operated from one cylinder only, in case of a breakdown or injury to the valve and valve-mechanism of the other cylinder.

A still further object of this invention is to provide a cylinder-construction and other parts of mechanism for an internal-combustion or explosive gas-engine which will be most simple in its design, the parts of which can be readily and conveniently assembled, and which will be inexpensive to manufacture and economical to run.

Other objects of this invention not at this time more particularly enumerated will be clearly understood from the following detailed description of the same.

With these various objects in view, the invention consists, primarily, in the novel internal combustion or explosive gas-engine herein-after more fully set forth; and, the invention consists, furthermore, in the various novel arrangements and combinations of the devices and parts, as well as in the details of the construction of the same, all of which will be more particularly described in the following specification, and then finally embodied in the clauses of the claim which are appended to and which form an essential part of this specification.

The invention is clearly illustrated in the accompanying drawings, in which:—

Figure 1 is a front elevation; and Fig. 2 a side view of an internal combustion or explosive gas-engine built according to and embodying the principles of the present invention. Fig. 3 is a longitudinal vertical section of the engine said view being made on an enlarged scale; and Fig. 4 is a transverse vertical section of the engine. Fig. 5 is a horizontal section of one of the engine-cylinders, said section being taken on line 5—5 in said Fig. 4; Fig. 6 is a plan view of one of the valve-mechanisms, the valve-stem being shown in cross-section; and Figs. 7 and 8 are face views of the respective ends of one of the pistons.

Similar characters of reference are employed in all of the above described views, to indicate corresponding parts.

Referring now to the several figures of the drawings, the reference-character 1 indicates the complete engine showing one embodiment of the principles of my present invention, and the same is provided with a suitably formed bed or base-plate 2, preferably made with a centrally disposed and thickened part 3, which is provided with bolt-receiving holes, as 4. The said bed or base-plate 2 may be provided with oppositely located openings 5, for lightness of construction, said bed or base-plate being also provided with a second set of oppositely located openings 6, substantially as shown in Fig. 5 of the drawings, and extending laterally across each opening 6 is a bearing 7, of any suitable construction. Mounted in said bearings 7 is a crank-shaft 8, provided in this case with a pair of crank-members or elements 9, which are rotatably arranged directly beneath said openings 6 and at times move into and through said openings, as will be clearly evident. Upon its one end-portion the shaft 8 is provided with a suitable pulley-wheel, as 10, over which a driving belt may be arranged, or in place of said pulley-wheel 10 any other driving means, such as a gear-wheel, or the like, may be used. The reference-character 11 indicates a movably arranged lever-arm, provided with a handle 12 and a laterally extending finger or member 13, carrying a pair of sockets 14 and 15, but insulated from said finger in any usual manner. The socket 14 is provided with a sliding contact or brush 16, and the socket 15 is provided with a sliding contact or brush 17, the respective contacts or brushes being provided with binding screws or clamps 18 and 19 for suitable attachment thereto of the conducting wires 20 and 21, leading from any suitable source of electrical energy. Suitably mounted upon and revolving with the said shaft 8 is a ring or cylinder 22 which is suitably insulated from the said shaft, and is provided with a pair of metal contacts 23 and 24, with which the respective contacts or brushes 16 and 17 make electrical connection, substantially in the manner and for the purposes to be hereinafter more fully described, and as will be evident from an inspection of Fig. 1 of the drawings. In order that proper electric circuits will be established between the shaft 8 and the respective metal contacts 23 and 24, at the proper times, the said metal contacts are inserted to such depths in the ring or cylinder 22, so that their inner surface-portions or bases will rest directly upon and be in contact with the metal shaft 8, in any ordinary and usual manner, and as will be clearly evident.

Resting upon the previously mentioned heavy or thickened part 3 of the bed or base-plate 2, and secured thereon by means of suitable bolts 25 and 26, is a cylinder 27, the upper end-portion of which is made with a flange 28 formed with bolt-holes 29. Extending across the upper portion of said cylinder 27 is a wall or member 29', from which extends in a downward direction and across and part-way into the upper inner chambered portion of the cylinder 27, a rectangularly formed guide-member 30, which is open at the top, as at 31, and in two sides, as at 32, the lower part of the member 30 being closed by means of a web or portion 33 which, however, is provided with an opening, as 34. The said cylinder 27 is also made with an enlarged and thickened part, as 35, which is provided with a cylindrical socket or receiving portion 36 having an internally screw-threaded part 37. Screwed into said socketed portion 36 is a hollow cylinder 38 made at its inner end with an annular valve-seat 39, upon which is normally seated a cone-shaped valve-disk 40. The said valve-disk 40 is provided with a valve-stem 41 which is slidably arranged in a guide 42 in the upper end-portion of the cylinder 38, said stem 41 being provided with a retaining-disk 43, or other suitable holding means, and a coiled spring 44, substantially as shown, and the purpose of which is to cause the valve-disk 40 to be normally seated upon the seat 39 and thereby close the said valve. The said cylinder 27 is also provided in one of its sides with an opening 45 which communicates with a receiving socket 46 upon the outside of the cylinder, and with which is connected an exhaust pipe 47. The said cylinder 27 is also made in one of its walls with a tubular channel 48, which communicates with the chamber or the interior of the cylinder, at 49 and 50, as shown, and thereby provides a suitable by-pass for the purposes to be presently more fully described. The said cylinder 27 is also surrounded by means of a suitably formed water-jacket 51 which is provided with a pair of screw-threaded pipe-receiving sockets 52 and 53. Resting upon the upper portion of the said cylinder 27 is a cylinder 54, said cylinder being provided upon its lower portion with a flange 55 formed with bolt holes 56, suitable bolts 57 being inserted through the bolt-holes 29 and 56, and provided with nuts 58 for permanently securing the said cylinder 54 upon the cylinder 27. Extending across the lower portion of the said cylinder 54 is a wall or member 59, from which extends in an upward direction and across and part-way into the lower inner chambered portion of the cylinder 54, a rectangularly formed guide-member 60, which is open at the bottom, as at 61, and in two sides, as at 62, the upper part of the member 60 being closed by means of a web or portion 63 which, however, is provided with an opening, as 64. The upper open portion of the said cylinder 54 is closed by means of a cylinder-head 65.

120
125
130

which is secured in place by means of screws or bolts 66, substantially as shown. The said cylinder 54 is also made with an enlarged and thickened part, as 67, which is provided with a cylindrical socket or receiving portion 68 having an internally screw-threaded part 69. Screwed into said socketed portion 68 is a hollow cylinder 70 made at its inner end with an annular valve-seat 71, upon which is normally seated cone-shaped valve-disk 72. The said valve-disk 72 is provided with a valve-stem 73 which is slidably arranged in a guide 74 in the upper end-portion of the cylinder 70, said stem 73 being provided with a retaining disk 75, or other suitable holding means, and a coiled spring 76, substantially as shown, and the purpose of which is to cause the valve-disk 72 to be normally seated upon the seat 71.

20 A tubular fitting or element 77 is suitably secured by means of screws or bolts 78 directly upon the two enlarged or thickened portions 35 and 67, substantially in the manner shown in Figs. 1, 2 and 4 of the drawings, the said fitting or element 77 being provided with a pipe-receiving portion 79, with which is connected an inlet-pipe 80, for conveying an explosive mixture or gas directly into said fitting or element 77 and to the said inlet-valves arranged in the socketed portions 36 and 68 of the respective enlarged parts 35 and 67. The said cylinder 54 is also provided in its side with an opening 81 which communicates with a receiving socket 82 upon the outside of the cylinder and with which is connected an exhaust pipe 83. The said cylinder 54 is also made in one of its walls with a tubular channel 84 which communicates with the chamber or 40 the interior of the cylinder, at 85 and 86, as shown, and thereby provides a suitable bypass for the purposes to be presently more fully described. The said cylinder 54 is likewise surrounded by means of a suitably formed water-jacket 87 which is provided with a pair of screw-threaded pipe-receiving sockets 88 and 89. Connected with the socket 88 is an inlet-pipe 90 for conducting a cooling medium, such as water, around the greater portion of the cylinder 54, and connecting the sockets 89 and 52 is a pipe 91 which conducts the water from the water-jacket 87 into the water-jacket 51 and around the lower cylinder 27, the water being finally conveyed, after it has performed its required work into an exhaust or outlet pipe 92 which is connected with the outlet 53.

Slidably arranged within the said lower cylinder 27 is a piston 93, said piston being provided with a pair of upwardly extending and curved wall or rib-like members or elements 94 and 95, the element 95 being made of greater height than the member 94, as shown. The said piston 93 has suitably

arranged upon its lower surface a member or element 96 which forms a shield, for the purposes to be presently more fully described.

Slidably arranged within the upper cylinder 54 is a piston 97, said piston being provided with a pair of downwardly extending walls or rib-like members or elements 98 and 99, the element 99 being made much longer than the member 98, substantially as shown, and for the purposes as will presently more fully appear. The said piston 97 has also suitably arranged upon its upper surface a member or element 100 which forms a shield, substantially as shown and for the purposes to be presently more fully described.

Slidably arranged in the rectangular space formed between the sides of the two guide-members 30 and 60 is a rectangularly formed bar or cross-head 101, the said bar or cross-head having its end-portions extending from the open sides of the said guide-members, substantially as shown in Fig. 3 of the drawings, and provided with journals 102. Connecting rods 103 are suitably arranged between the said journals 102 and the crank-members or elements 9 of the shaft 8, the said connecting rods 103 being operatively retained upon the journals 102 by means of nuts 104 which are screwed upon the screw-threaded stud-like members 105 extending from the end of each journal 102. The said bar or cross-head 101 is also made with a screw-threaded-receiving portion 106 into which are screwed the screw-threaded end-portions 109 and 110 of a pair of piston-rods 107 and 108, substantially as illustrated in Figs. 3 and 4 of the drawings. The piston-rod 107 is made with a reduced portion 111 upon which the piston 93 is arranged and is secured in place by means of a nut 112 screwed down upon a screw-threaded end-member 113. In a like manner, the piston-rod 108 is made with a reduced portion 114 upon which the piston 97 is arranged and is secured in place by means of a nut 115 screwed down upon a screw-threaded end-member 116. Thus it will be clearly evident, that the two reciprocating pistons are connected practically by means of a piston-rod intermediately arranged between the two pistons, and the return movement of the one piston, caused by the explosion of the gas between the end of the cylinder and the previously forwardly moved piston, will produce simultaneously with the movement of said piston, a forward movement of the other piston, and vice versa.

Connected with the thickened part 3 of the bed or base-plate 2 is a suitably constructed electric sparker, as 117, to which is attached a circuit-wire 118, the jump-spark producing members of the said sparker being located within the lower end of the cylinder 27; and, suitably connected with the

cylinder-head 65 of the cylinder 54 is another suitably constructed spark 119 to which is attached a circuit wire 120, the jump-spark producing members of said 5 sparker being located within the upper end of the cylinder 54, all of which is clearly illustrated in Figs. 3 and 4 of the drawings.

Having thus described the general arrangement and construction of the devices 10 and parts of one form of internal combustion or explosive gas-engine embodying the principles of my present invention, I will now briefly set forth the operation of the engine. Suppose the pistons 97 and 93 having been simultaneously moved into the positions indicated in Figs. 3 and 4 of the drawings, in which positions the previously taken in explosive mixture or gas has been compressed in the space between the piston 20 97 and the cylinder-head 65, and is just about to be ignited by means of the jump-spark at the electrodes of the electric spark 119. At the same time, the previous movement of the piston 97 in its forward direction, that is in the direction of the arrow α in Fig. 4, has by suction sufficiently displaced the valve-disk 72 from the valve-seat 71 to admit of a fresh supply of the gaseous mixture upon the opposite side of 30 the piston 97. It will be seen, that the downwardly projecting marginal rib-like member or element 99 forms a guard which is moved over the exhaust-outlet 81, so that the freshly admitted gaseous mixture can 35 not escape from the cylinder 54, which will be clearly evident from an inspection of Fig. 4. During the same time, the return movement of the piston 93 in the direction of the arrow α in said Fig. 4, forces the 40 gaseous mixture which has been previously taken into the cylinder 27, by the displacement of the valve-disk 40 from the valve-seat 39, into the inlet-opening 49 and through the duct 48 and out of the outlet 50 upon the opposite side of the piston 93, the member or element 96 serving as a shield and a deflector to direct the entering gas in a direction away from the exhaust-outlet 45, through which the previously exploded 55 gas has escaped and has been exhausted from the pipe 47. An electric spark now being produced by the spark 119, the compressed gas between the piston 97 and the cylinder-head 65 is ignited and exploded 60 and thereby drives the two pistons 97 and 93 simultaneously in the direction of the arrow y , indicated in Fig. 4. This movement of the piston 93 now compresses the 65 gas in front of the piston 93 and the part 3 of the bed or base-plate, to be exploded by the electric spark produced at the electrodes of the electric spark 117, at the same time taking in by suction through the inlet-valve in the side of the cylinder 27, a fresh charge of the explosive mixture or gas, and the

member or element 95 which has moved over the exhaust opening 45 preventing the escape of the mixture from the cylinder 27. As soon as the piston 97 in the other cylinder 54 moves past the exhaust-opening 81, the 70 exploded gas in said cylinder passes through said opening 81 and is exhausted from the pipe 83. During the return stroke or movement of the piston 97 in the direction of the arrow y , the previously taken-in charge of 75 gaseous mixture in said cylinder 54, as soon as the piston 97 has passed the outlet-opening 85, is forced into the inlet-opening 86, through the duct 84 and from the outlet-opening 85 upon the opposite side of the 80 piston 97, there to be compressed when the piston again moves in the direction of the arrow α , and to be exploded at the proper moment. Thus it will be clearly evident, that with the reciprocatory movements of 85 the pistons, within their respective cylinders, an explosion takes place during the forward stroke of each piston, a fresh charge of gaseous mixture being at the same time taken into the same cylinder in which the explosion takes place, whereby the said 90 fresh charge of gas is sufficiently heated up, so that there can be no failure of its ignition when directed to the exploding point in the cylinder. It will also be clearly evident, 95 that while the explosions of the gaseous mixture take place upon each end of a piston only, such explosions take place intermittently and in such rapid succession, so that the cross-head or bar 101 moves easily 100 and freely back and forth in the guide formed by the two guide-members 30 and 60, so as to produce by means of the connecting rods 103 and the crank-members 9, uniform revolutions of the shaft 8.

Of course it will be understood, that the engine according to my invention may be made in multiple form, if desired. I am also aware, that changes may be made in the various arrangements and combinations of the devices and parts, as well as in the details of the construction of the same, as described in the foregoing specification, without departing from the scope of this invention as defined in the appended claims. Hence I do not limit my invention to the exact arrangements and combinations of the various devices and parts as described in the foregoing specification, nor do I confine myself to the exact details of the construction of any of the said parts, as illustrated in the accompanying drawings.

I claim:

1. An internal combustion engine comprising a pair of cylinders secured end to end, the adjacent end-walls of said cylinders being each formed with a rectangularly formed guide-member, each guide-member extending part-way into a cylinder, a piston in each cylinder, a cross-head slidably 125

130

arranged in said guide-members, and a piston-rod between each piston and said cross-head, substantially as and for the purposes set forth.

2. An internal combustion engine comprising a pair of cylinders secured end to end, the adjacent end-walls of said cylinders being each formed with a rectangularly formed guide-member, each guide-member extending part-way into a cylinder, a piston in each cylinder, a cross-head slidably arranged in said guide-members, and a piston-rod between each piston and said cross-head, said guide-members being open at their sides and extending laterally across

and forming portions of said cylinders, so as to provide an opening in the opposite side of each cylinder, journals extending from said cross-head through the openings in the sides of said cylinders, a crank-shaft, and a connecting rod between each journal and the crank-shaft; substantially as and for the purposes set forth. 20

In testimony, that I claim the invention set forth above I have hereunto set my hand 25 this 24th day of June, 1908.

EUGÈNE MUNSCH.
